UNITED STATES PATENT OFFICE.

MARIUS P. P. RIIS, OF SEATTLE, WASHINGTON, ASSIGNOR TO FOREST BY-PRODUCTS COMPANY, OF SEATTLE, WASHINGTON.

MECHANICAL AGITATOR.

1,247,013.

Specification of Letters Patent. Patented Nov. 20, 1917.

Application filed December 28, 1916. Serial No. 133,826.

To all whom it may concern:

Be it known that I, MARIUS P. P. RIIS, a citizen of the United States, and a resident of Seattle, in the county of King and State 5 of Washington, have invented certain new and useful Improvements in Mechanical Agitators, of which the following is a full, true, and exact specification.

My invention relates to mechanical agitators and more particularly to that class of agitators which are used to agitate heavy liquids such as might be used in the wood and coal tar distillation industries. The principal objects of this invention are to 15 provide an improved and novel type of agitator which embodies paddles revolving in a vertical plane and at the same time rotating horizontally.

Other objects will appear as my invention 20 is more fully explained in the following specifications, illustrated in the accompanying drawings and pointed out in the appended claim.

In the drawings, Figure 1 is a side elevation of my device with parts broken away 25 along a vertical center line. Fig. 2 is an end elevation of a yoke detail. Fig. 3 is a plan view taken along line 3—3 of Fig. 1. Fig. 4 is an enlarged detail and fragmentary 30 plan view of the extreme bottom of the agitator tank. Fig. 5 is an enlarged side elevation of paddle rotating mechanism with parts broken away. Fig. 6 is a cross sectional elevation along line 6—6 of Fig. 1.

Referring more particularly to the drawings, numeral 7 indicates a cylindrical tank having a hemispherical bottom 8 and a cover 9. An inner shaft 10 is mounted vertically and centrally within tank 7 and takes 35 bearing in a foot block 11 at the bottom of the tank 7. An outer tubular shaft 12 fits revolvably over shaft 10 and extends from above tank 7 down to the paddle revolving mechanism. A supporting bracket 13 supports shaft 12 and may be secured to a 40 frame work if so desired. The outer shaft 12 is caused to revolve by gearing, belting or other standard transmission means while the inner shaft 10 remains stationary. A 45 fluid tight box 14 incloses the mechanism operating paddles 15. There are eight (more or less) similar paddles 15 which are mounted in groups of four (more or

less) each upon similar shafts 16. The shafts 16 are oppositely disposed and perpendicular to shaft 10 and at their inner ends take bearing in a bearing block 17 which is secured to the lower end of outer shaft 12 and which revolves with the said shaft. The outer ends of shaft 16 take 55 bearing in the ends of a bail 18 which is secured to shaft 12. The ends of bail 18 are connected by means of a hoop 19. Gears 20 are secured to the inner ends of shaft within box 14 and coöperate a drive gear 60 21 which is secured to inner shaft 10 so that the gear 21 remains stationary while the gear 20 revolves about the gear 21. The paddles 15 are similar and are formed of slatted or open work construction. Up- 65 standing mixers 22 are secured to the upper portion of bail 18 and also assist in agitating the liquid in the tank. It will be understood that when the shaft 12 is in motion that the bail 18 and shafts 16 revolve 70 in horizontal planes with the shaft 12 and that the shafts 16 revolve about their axis and cause the paddles 15 to also revolve about the axis of shafts 16.

My device has been found particularly 80 well adapted to agitating liquids such as coal tar and wood tar distillates in the distillation of wood oil and acetates, or any liquid which has a tendency to separate due to the specific gravity of the constituents. 85

While I have shown a particular form of embodiment of my invention, I am aware that many minor changes therein will readily suggest themselves to others skilled in the art without departing from the spirit 90 and scope of the invention, and I therefore desire to avoid being limited to the exact form shown and described.

Having described my invention, what I 95 claim as new and desire to protect by Letters Patent, is—

A device of the class described including a stationary shaft, a tubular revoluble shaft about said stationary shaft, a plurality of radial paddle shafts and enmeshing gears 100 connecting said paddle shafts and said stationary shaft, a bail secured to said tubular shaft, a hoop secured to the ends of said bail and end bearings for said radial shafts in said hoop.

MARIUS P. P. RIIS.
